CAP BAIL RESHAPING TOOL

Walter J. Smith, Penn Yan, N. Y.

Application June 21, 1934, Serial No. 731,756

4 Claims.

(Cl. 81—15)

This invention relates to tools, and its general object is to provide a tool that is primarily designed for use in reshaping clamping bails for the caps of jars and the like, to make the bails useable from time to time and with the same efficiency and clamping qualities as when new, with the result the expense of renewing the bails will be eliminated.

Another object of the invention is to provide a tool for reshaping jar cap bails of various sizes in an easy and expeditious manner and with very little effort.

A further object of the invention is to provide a reshaping tool of the character set forth, that is simple in construction, inexpensive to manufacture and extremely efficient in use and service. This invention also consists in certain other features of construction and in the combination and arrangement of the several parts, to be hereinafter fully described, illustrated in the accompanying drawing and specifically pointed out in the appended claims.

In describing my invention in detail, reference will be had to the accompanying drawing wherein like characters denote like or corresponding parts throughout the several views, and in which:

Figure 1 is a top plan view of the tool which forms the subject matter of the present invention.

Figure 2 is a side view thereof.

Figure 3 is a sectional view taken approximately on line 3—3 of Figure 2, looking in the direction of the arrows, and shows the lower portion of the tool.

Figure 4 is a similar view of the upper portion.

Figure 5 is a sectional view taken approximately on line 5—5 of Figure 1 looking in the direction of the arrows.

Figure 6 is a sectional view taken approximately on line 6—6 of Figure 2, looking in the direction of the arrows.

Referring to the drawing in detail, it will be noted that my tool includes companion members which may be broadly referred to as an upper member and a lower member that cooperate to reshape bails of jar caps in a manner which will be later apparent.

The lower member includes a relatively large hollow body 1 in the form of a frame that is substantially diamond shape in configuration, as best shown in Figure 3 and the body has formed thereon a shank portion 2 that extends into a handle 3, it being noted that the body, the shank portion and handle are integral and are formed

from a single strip of material bent into configuration for that purpose, as shown. The portions of the strip which form the shank are disposed in contacting engagement and held accordingly through the instrumentality of rivets and the portions of the strip providing the handle are spaced with respect to each other to form a convenient gripping means.

The body is relatively wide to provide what may be termed a chamber and has arranged in opposed corners thereof for bridging the same, webs 4 which have upturned flanges 5 formed on the inner edges thereof as clearly shown in Figure 3. The said opposite corners are looped upon themselves to provide channels 6 that are disposed diametrically opposite each other and arranged laterally of the channels 6 are loops which provide channels 7 that are likewise disposed diametrically opposite each other. Aligned with the channels 6 and rising from the webs 4 are rectangular members providing seats 8.

The body extends into spaced parallel ears 9 at the outer ends of the strips of material and these ears are apertured for the purpose of receiving a headed pin 10 to pivotally receive the outer ends of the spaced parallel arms 11 that form a frame like body for the upper member of my tool, it being noted that the arms 11 are upwardly curved from their pivotal connection with the pin 10 and thence extend into converging portions 12 that merge into a shank 13 which has formed therewith a handle 14, the latter cooperating with the handle 3 in the use of the tool, as will be apparent.

Bridging the converging portions 12 is what may be termed a platform 15 which has threadedly mounted therein a set screw 16 having a handle 17, and which cooperates with a bridging piece 18 that extends across the inner end of the body 1 for disposal in the path of the lower end of the set screw, for the purpose of regulating the space between the respective upper and lower members of my tool during the use thereof.

Secured to the arms 11 through the instrumentality of a headed pin as best shown in Figure 6 is the block portion 19 of a grooved member 20 that extends upon opposite sides of the arms 11 and at right angles with respect thereto. The member 20 has longitudinally disposed therein a pair of parallel arranged grooves 21 and 22, the groove 21 cooperating with the channels 7 while the groove 22 cooperates with the channels 6 during the use of my tool.

From the above description and disclosure of the drawing, it will be noted that my tool is designed to reshape at least two sizes of jar cap

bails, there being two popular sizes now in general use, one bail which is indicated by the letter A being the size for use with a cap for a $3\frac{1}{4}$ inch jar, while the bail B is for use upon a cap for a $4\frac{1}{4}$ inch jar. In reshaping the bail A, it is placed within the tool in a manner whereby the lateral arms thereof are disposed within the channels 7, while the trunnion ends engage the flanges 5, as clearly shown in Figures 3 and 6. The upper member is then swung downwardly on its pivot so that the bight portion of the bail is received in the groove 21, it being understood that the set screw 16 is arranged at a position to limit the movement of the upper member for properly reshaping the bail, as suggested in Figure 6.

15 The bail B which is of the larger size, is placed within the body 1, so that the lateral portions extend into the channels 6 and the trunnion ends engage the seats 8, so that the bight portion thereof is arranged in the path of the groove 22, with the result the bails will be reshaped to make them useable with the same efficiency and clamping action as when new.

20 It is thought from the foregoing description that the advantages and novel features of my invention will be readily apparent.

25 I desire it to be understood that I may make changes in the construction and in the combination and arrangement of the several parts, provided that such changes fall within the scope of the appended claims.

30 What I claim is:

35 1. A bail reshaping tool comprising a pair of pivoted members mounted for clamping association with respect to each other, handles for said members, a hollow body for one of said members and being of substantially square cornered configuration, said body having bail receiving channels arranged in two diametrically opposite corners, means to receive the trunnion ends of the bails and cooperating with the channels, grooved means secured to the other member for clamping engagement with the bails, and means to limit the movement of said members with respect to each other.

40

45 2. A bail reshaping tool comprising a pair of pivoted members mounted for clamping association with respect to each other, handles for said members, a hollow body for one of said members and being of square cornered configuration, said body having bail receiving channels in diametrically opposite corners, webs bridging the said corners, bail trunnion receiving means secured to said webs, grooved means carried by the other member with the groove arranged to cooperate with the channels and trunnion receiving means in reshaping the bails, screw means carried by the last mentioned member and means arranged in the path of the screw means and cooperating therewith to regulate the position of the members with respect to each other.

50 3. A bail reshaping tool comprising a lower member, an upper member pivotally secured to the lower member for clamping association therewith, handles for said members, a frame like body for the lower member and having diametrically opposed corners, bail receiving means arranged in and adjacent to said corners for holding bails in position to be reshaped, means carried by the upper member and notched to receive and engage the bails, said notched means cooperating with the bail receiving means for reshaping the bails, and adjustable means for limiting the clamping relation of said members with respect to each other.

55 4. A bail reshaping tool comprising a lower member, an upper member pivotally secured to the lower member for clamping association therewith, handles for said members, a frame like body for the lower member, diametrically opposed bail receiving channels carried by the body, bail seats for the bail receiving channels and cooperating therewith for supporting bails in a position to be reshaped, bail engaging means carried by the upper member for cooperation with the channels and seats for reshaping bails, and means to limit the movement of the members with respect to each other.

60 WALTER J. SMITH.
